UNITED STATES PATENT OFFICE.

JOHN H. HINKEN, OF LOUISVILLE, KENTUCKY, AND JOHN E. TURNER, OF OAK PARK, ILLINOIS, ASSIGNORS TO THE J. E. TURNER DRYING MACHINERY COMPANY, OF CHICAGO, ILLINOIS.

PLATE FOR FILTER-PRESSES.

SPECIFICATION forming part of Letters Patent No. 651,546, dated June 12, 1900.

Application filed July 21, 1899. Serial No. 724,618. (No model.)

To all whom it may concern:

Be it known that we, JOHN H. HINKEN, a citizen of the United States, residing at Louisville, county of Jefferson, and State of Kentucky, and JOHN E. TURNER, a subject of the Queen of Great Britain, residing at Oak Park, county of Cook, and State of Illinois, have invented certain new and useful Improvements in Plates for Filter-Presses, which are fully set forth in the following specification, reference being had to the accompanying drawings, forming a part thereof.

This invention relates to the class of presses which are used to separate solid from liquid matter by process of filtering under pressure; and it consists in improvements in the structure of the plates used in such presses to afford backing for the filtering or straining element and in the combination therewith of certain features, as set out in the claims.

In the drawings, Figure 1 is an axial section of a filter-press having our improvements. Fig. 2 is a section at the line 2 2 on Fig. 1, showing in elevation one of the filter-plates, the filtering fabric and woven-wire cloth or screen which backs it, each partly being broken away to disclose the structure underneath. Fig. 3 is a detail section, full size, through a filtering-plate of our improved construction at the line 3 3 on Fig. 2. Fig. 4 is a similar full-size detail section at the line 4 4 on Fig. 2.

The general arrangement of the parts in our improved press is similar to that shown in patent to John H. Hinken, No. 607,929, dated July 26, 1898; but the detail structure is different from that shown in said patent, as will be indicated by the following description.

Both the filtering-plates A A A and the end plates B and B' are made of wood, preferably built up of narrow strips glued together edge to edge and additionally secured, so as to form substantially-integral planks, by means of bolt-rods C C C, &c., extended through each plate from edge to edge, said strips being also suitably doweled together at their abutting edges, as shown, by the dowel-pins a a. The intermediate plates A A A and the

head-plate B at one end are provided each 50 with an induction-aperture 1, preferably at the center, though this is a matter of convenience or symmetry rather than of necessity, as respects the function or operation of the press. All the plates A A A and B B' ride on the 55 rods G G of the press-frame, said rods being supported at opposite ends on the posts D D D. When suspended on the rods, the several filter-plates are coaxial, the induction-apertures being in line, and the rear end 60 plate B' is provided with a swiveled stem E, which is screw-threaded at its exposed or protruding portion and screwed through a cross-head D', which secures the posts D D at that end, said swiveled and threaded stem having 65 an operating-handle E', by which it may be screwed back and forth through the cross-head to close or open up the press. The induction-head B is stopped in any suitable manner, so that the entire assemblage of 70 plates may be closed up upon the rings H, which are interposed between them and constitute the walls of the cells which are formed between the plates.

J is the clearing-blade, formed as a continuation of its shaft J' and extending in through the induction-pipe K and through the induction-apertures of the several plates, the structure in this respect and the mode of operation being that shown in said Patent No. 75 80,607,929.

The features constituting our present invention relate to the construction of the plates and their surface-coverings, which will now be described. Said plates being formed, 85 as already mentioned, of wood, have vertical grooves 3 3, &c., on their faces constituting the walls of the cells, the interior plates A A A therefore being grooved on both faces and the end plates on the inner faces only. 90 These filter-grooves are in cross-section about three-sixteenths of an inch wide and deep and separated by intervals about equal to their width. At their lower ends they lead into a drainage-channel 4, which follows the 95 lower edge of the plate, extending, therefore, around about half the circumference of the cell at the lower side. Around the induction-

apertures there is necessarily left standing of each interior surface of the filter-plates an ungrooved portion 5, the filter-grooves being constructed by the same, since otherwise the unfiltered material entering through the induction-apertures would obtain direct access into the filter-grooves. This circumstance, in the absence of provision to the contrary, would prevent the drainage of the upper portion of such of the filter-grooves as are thus obstructed; and to prevent this we form a transverse drainage-channel 6 a little above the ungrooved annular central portion 5, said transverse drainage-channel having a length greater than the diameter of said ungrooved center and extending beyond it at both sides, so that the filter-grooves crossed by it are thereby drained laterally into other filter-grooves which are not obstructed. It will be manifest that the liquid forced through the filtering fabric into the filter-grooves equally at all points of the surface, if it were sufficient in quantity to require the entire capacity of the filter-groove to receive it, could not be carried off by these same filter-grooves, because the supply at the lower portion of each groove would use the full capacity of the groove, and that which would be forced into the groove at the upper portion would find no escape until that in the lower portion had been drained off. This would result in unequal filtering of the material, the lower portion of each cell becoming filled with solid residuum, while the upper portion was still occupied with unfiltered liquid. To prevent this undesired result, we provide drainage-channels 7, extending obliquely across the filter-grooves, diverging from a point near the upper edge of the cell toward opposite sides, so that the upper portion of all the grooves thus crossed may be drained directly through this channel, down to the lower part, avoiding the necessity of passing the liquid from such upper portion of each filter-groove down through the same groove to the final drainage-channel, and to the same end we provide another pair of oblique drainage-channels 8, preferably connecting with the lower ends of the channels 7, respectively, and converging from opposite sides toward the lower edge of the cell. These lower converging drainage-channels take the liquid not only from the upper diverging channels 7, but also from the portion of the filter-grooves which extends up and down between the channels 7 and the channels 8, thus almost entirely relieving the portion of the filter-grooves below the converging channels 8 of the duty of conducting away the liquid from the upper portion of the same. It will be understood that from any suitable point—preferably the lowest point—in the final drainage-channel 4 a suitable outlet-duct leads through the edge of each plate, as illustrated at 9, &c., such outlet being provided with a discharge-spout 10.

One of the difficulties which greatly limits the filtering capacity of a press of this character arises from the manifest fact that the filtering, practically or very nearly, is confined to the portion of the area of the filter-cloth which overlies the grooves and channels, because the cloth, being forced onto the surface of the plate by the pressure which is to effect the filtering, there is no escape for the liquid back of the fabric, except when the surface of the plate is recessed for that purpose. The same circumstance causes the strain upon the filtering fabric at the edges of the grooves to be very great and causes great liability to parting the threads at these edges, so that even when the fabric does not break apertures are opened between the threads large enough to admit solid material and prevent proper filtration. The last-mentioned difficulty is largely overcome by the construction described in said Patent No. 607,929, involving the application of the fabric biaswise with respect to the filter-grooves; but the first defect—limitation of the available filtering area of the fabric to the area of the grooves and channels—still remains in that structure.

By our present improvements we largely overcome the defect in respect to limiting the filtering area, and at the same time we overcome the other defect mentioned in a different manner from that described in said former patent. For these purposes we apply upon the surface of the filtering-plates over the grooves or channels open-meshed woven-wire fabric or screen L, such fabric of half-inch-square mesh being found quite effective and satisfactory in use, the same being laid on biaswise with respect to the filter-grooves—that is, so that both wires of the screen lie obliquely across the filter-grooves. Over this woven-wire fabric or screen the filter-cloth M, of customary web and character, is applied, and may be laid without regard to direction of its threads. The woven-wire backing L terminates inside the cell-wall and is secured by suitable tacks to the wood at as many points as found necessary; but the filtering fabric extends beyond the cell-wall and may be secured outside the same by suitable tacks or nails driven into the wooden plates in the margin which is left outside the cell-walls and made ample for this purpose. The cylindrical cell-walls H are stepped at their edges on the surface of the fabric, which is thus securely held and also serves when the cells are closed up to pack the joint. By reference to Fig. 3 it will be seen that the crossing of the wires of the screen L leaves adjacent each wire, between the crossing-wire and the adjacent surface of the plate, a clear space or crevice 11, and that even though the filtering fabric M should be sunken into the half-inch-square mesh of the screen it cannot close this crevice 11, and that there is thereby produced a network of these crevices or filamentary channels alongside the wires in each

direction extending over the whole surface of the supporting-plate, so that even without any filtering-grooves quite a large area of the filtering fabric M would be exposed over these spaces instead of being pressed tightly onto the backing-plate; and that therefore quite a large measure of filtration would occur without any grooves in the plate, and the filtered liquid would find escape downward through this network of crevices. When such screen is applied over the grooved plate, of course the area of cloth exposed is very greatly increased and the circulation or drainage of the liquid behind the cloth is very much more free than if the screen were applied merely upon an ungrooved plate or if the cloth were applied directly upon a grooved plate. It will be manifest that the screen-wires giving both threads of the fabric support at intervals of half an inch overcomes the difficulty and defect arising from the application of the filtering fabric upon the grooved plate with its threads one way extending in the same direction as the grooves and that while there is some additional advantage of this nature obtained by applying the cloth biaswise with respect to the screen-wires it is not essential that it should be so applied. In the drawings the screen L is applied bias with respect to the grooves at an angle of about thirty degrees by sixty degrees, so that the drainage-channels 7 and 8, which are shown at angles of forty-five degrees to the grooves, may not coincide exactly with any wires of the screen, and when thus placed the filtering fabric M may be applied so that its threads will be oblique not only to the wires of the screen, but to the grooves and channels of the plate. Theoretically such oblique arrangement of all the elements is the best; but practically there is no absolute necessity for carrying the principle to this extreme, and we do not limit ourselves strictly in this respect.

45 We claim—

1. In a filter-press, a filter-plate having up-and-down filter-grooves, a final drainage-channel into which they lead at their lower ends, and oblique drainage-channels crossing the grooves diverging downward from near the upper edge toward the opposite sides.

2. In a filter-press, a filter-plate having up-and-down filter-grooves, a final drainage-channel into which they lead at their lower ends, and oblique drainage-channels crossing the 55 grooves and converging downward from opposite sides toward the lower edge.

3. In a filter-press, a filter-plate having up-and-down filter-grooves, a final drainage-channel into which they lead at their lower ends, 60 oblique drainage-channels crossing the grooves diverging downward from near the upper edge toward the opposite sides, and oblique drainage-channels crossing the grooves and converging downward from opposite sides 65 toward the lower edge.

4. In a filter-press, a filter-plate having up-and-down filter-grooves, and a final drainage-channel into which they lead at their lower ends, and having an induction-aperture, and 70 an ungrooved annular portion about the same, and a transverse drainage-channel crossing the grooves above the entire width of the ungrooved annular part and extending laterally beyond the same in both directions, whereby 75 the liquid filtered into the up-and-down grooves finds the way past the ungrooved annular part toward the final drainage-channel.

5. In a filter-press, a filter-plate having filter-grooves in its surface, and an open-meshed 80 wire cloth or screen applied on such surface with the wires both ways oblique to the filter-grooves, and filtering fabric applied outside the screen with its threads both ways oblique to the wires of the screen. 85

6. In a filter-press, a filter-plate having filter-grooves in its surface, and an open-meshed wire cloth or screen applied on such surface with the wires both ways oblique to the filter-grooves, and filtering fabric applied outside 90 the screen with its threads both ways oblique both to the filter-grooves and to the wires of the screen.

In testimony whereof we have hereunto set our hands, at Louisville, Kentucky, this 15th 95 day of July, 1899.
